(57) **CLAIM**

The ornamental design for a cup, as shown and described.

DESCRIPTION

FIG. 1 is a perspective view of a cup, showing our new design;

FIG. 2 is a reverse side view of the cup shown in FIG. 1; FIG. 3 is a front side view of the cup shown in FIG. 1; FIG. 4 is a left side view of the cup shown in FIG. 1; FIG. 5 is a right side view of the cup shown in FIG. 1; FIG. 6 is a top view of the cup shown in FIG. 1; and, FIG. 7 is a bottom view of the cup shown in FIG. 1.

The broken line showing of portions of the cup is for the purpose of illustrating unclaimed environmental structure only and forms no part of the claimed design.

1 Claim, 7 Drawing Sheets
